(57) **CLAIM**

The ornamental design for a welding cart, as shown and described.

DESCRIPTION

FIG. 1 is a front, top perspective view of a welding cart showing my new design;

FIG. 2 is another perspective view thereof;

FIG. 3 is another perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

The broken lines shown in the figures are included for the purpose of illustrating environment and form no part of the claimed design.
